UNITED STATES PATENT OFFICE.

ANGELO C. MESSINA AND JOSEPH MESSINA, OF PITTSBURGH, PENNSYLVANIA.

LOCK.

Application filed January 2, 1923. Serial No. 610,132.

To all whom it may concern:

Be it known that we, ANGELO C. MESSINA and JOSEPH MESSINA, citizens of the United States, residing at Pittsburgh, in the county 5 of Allegheny and State of Pennsylvania, have invented certain new and useful Improvements in Locks, of which the following is a specification.

This invention relates to certain new and 10 useful improvements in locks of a type somewhat similar to the construction disclosed in United States Patent No. 1,435,320.

The objects of the invention are to provide a substantial lock which is adaptable for 15 various uses, which includes a hinged cover plate having disguised latching means operable only by persons acquainted with its construction, which is simple in its construction and arrangement, strong, durable and 20 efficient in its use, and comparatively inexpensive to manufacture.

To the accomplishment of these and such other objects as may hereinafter appear, the invention consists of the novel construction, 25 combination, and arrangement of parts herein specifically described and illustrated in the accompanying drawing, wherein is shown an embodiment of the invention but it is to be understood that changes, variations and 30 modifications may be resorted to which come within the scope of the claims hereunto appended.

In the drawing forming a portion of this 35 specification and wherein like numerals of reference designate corresponding parts throughout the several views:—

Figure 1 is a front elevation of a lock in accordance with this invention.

Figure 2 is a similar view with the casing 40 cover removed and the cover plate and hasp elements in the open position.

Figure 3 is a front view of the casing cover.

Figure 4 is a perspective view of the 45 locking bolt.

Figure 5 is a side view of one of the hasp elements.

Figure 6 is a perspective view of a tumbler element and the spring associated 50 therewith.

Figure 7 is a perspective view of the latching device for securing the cover plate.

Figure 8 is an elevation of the key for 55 operating the tumbler elements as illustrated.

Figure 9 is a modified form of attachment device adaptable for use in connection with the hasp elements of our improved lock mechanism.

Referring in detail to the drawing 1 denotes the lock casing provided at its upper end with an integrally formed bar 2 having projecting ends 3 and 4, respectively. The bar end 4 is formed with an arm 5 disposed at right angles thereto, which latter carries 60 a fixed shackle 6 extending in parallel with respect to the bar 2. While the casing 1 is preferably circular in contour with the exception of the straight upper end, it will be obvious that its configuration may 65 be varied to meet desired conditions.

Formed integral in the casing 1, adjacent to the bar end 4, is a spindle 8, on which 70 four tumblers 9, 10, 11 and 12 are pivotally mounted. The tumblers are constructed 75 from flat metal and are positioned upon each other. When in the locking position the tumblers are positioned angularly or diagonally within the casing 1.

All of the tumblers 9, 10, 11 and 12 are 80 identical in construction with the exception of their curved operating lips 13, which vary in width to conform to the ward 14 designed therefor, of the key 15. The tumblers may be transposed or interchanged in the order of 85 mounting them upon each other, so as to require differently arranged key wards to effect their shifting to the unlocking positions. The number of tumblers may also be varied as desired, to provide manifold 90 key designs to effect the unlocking operation.

Each of the tumblers 9, 10, 11 and 12 is formed on one edge thereof with a curved 95 recess 16, open at its lower end and forming the nose 17 for the purpose to be described. A flat spring 18 is fixed to the edge of each 100 of the tumblers at a point below the opening of the recess 16. The upper end of each spring 18 rests against the guide post 19 which latter is formed integral with the casing 1. The normal action of the springs 18 is to force respective tumblers against the locking bolt spindle 20 fixed in the casing 1.

The locking bolt 21 is pivotally mounted 105 on the spindle 20, which engages in the aperture 20', and is formed with curved ends 22 and 23 extending in opposite directions relatively to each other, so that when the bolt is shifted the former will be moved downwardly and the latter upwardly. The 110

bolt 21 carries a pin 24 on its inner face extending into the recess 16 formed in the superposed tumblers 9, 10, 11 and 12 as herein before described.

5 When the bolt 21 is in the locking position, as shown in Figure 2 of the drawing, the pin 24 will be engaged by the nose 17 of each of the tumblers holding the bolt 21 fixed in the locked position until the tumblers are shifted by the key to cause the travel of the pin 24 in the curved recesses 16. The locking bolt 21 is controlled by a flat spring 25 which is mounted on the spindle 8. One leg of the spring 25 engages the inner wall 18 of the bar 2 while the other leg thereof engages the edge of the locking bolt 21. The spring 25 normally functions to return the bolt 21 to the locking position.

20 The casing 1 is provided with a cover plate 26 which is secured to the former by means of screws 27 passing through the countersunk openings 28 in the plate 26 and engaging the respective threaded apertured bosses 29 formed integral with casing 1.

25 A pair of hasp members 30 and 31, each having a sleeve shaft 32 fixed in its upper end, is hingedly and slidably mounted on the shackle 6. The upper end of each of the hasp members 30 and 31 is formed with a centrally disposed slot 33 and a link 34 is pivotally mounted therein on the sleeve shaft 32. Each of the hasps 30 and 31 is provided on its inner face with a staple 35 adapted to extend through respective slots 36, provided therefor, in the casing cover 26, and be engaged by respective curved ends 22 and 23 of the locking bolt 21 when in the locked position. Each of the staples 35 is formed with a tapered lower portion 37 and 40 is slightly resilient, so that the hasps 30 and 31 may be forced to the locked positions without the use of the key if desired.

45 A cover plate 38 is hinged to the lower portion of the casing 1 and is provided with a staple 39 adapted to be engaged by a disguised latch member 40 through slot 41 in the upper portion of the casing cover 26, for maintaining the cover plate in the closed position.

50 A flat spring 42 is mounted on the inner face of the cover plate 38 and is provided for the purpose of throwing the latter to the open position when the latch member 40 is released. The cover plate 38 is provided for concealing the key hole 43 and can be released only by the manipulation of the operating arm 45 which forms a portion of the latching member 40.

60 The operating arm 45 of the latch 40 is shiftably mounted in a groove 44 formed in the top edge of the casing wall 2. A portion of the latching member 40 is disposed within the casing 1 and slidably engages a slot formed in the guide post 19. The construction of the arm 45 is such that when in the

latched position it ostensibly forms an integral portion of the wall 2 which is not readily detected by one not acquainted with its construction. A coil spring 46 is mounted in the casing 1 and engages the latching member 40. The action of the spring 46 normally holds the latching member 40 in the latched position.

65 The locking bolt 21 is formed with a depending lug 47 which is adapted for engagement with the ward of the key to shift the bolt 21 to the unlocking position simultaneously with the shifting of the tumblers 9, 10, 11 and 12.

70 The embodiment of the device shown in Figure 1 illustrates the links 34 attached with a chain 48 primarily adapted for securing a spare automobile tire to prevent the possible theft thereof.

75 The modification shown in Figure 9 illustrates the attachment of the device for securing a door 49, or similar structure. A staple 50 is fixed to the door 49 and an aligned staple 51 to the adjacent structure 52. Each of the hasp elements 53 carry a fixed tubular shaft 55 which also passes through respective staples 50 and 51. The shackle 54 is withdrawn from the shafts 50 in a manner identical to the form hereinafter described.

80 What we claim is:—

1. A lock comprising a casing provided with a slot, and an integrally formed shackle, a hasp member provided with a staple which latter is adapted to extend into the casing through said slot, a locking bolt capable when shifted to locking position of extending through said staple whereby the hasp member is locked in the casing, means for shifting the said bolt to release the hasp, a sleeve slidably mounted on said shackle, said hasp member fixedly connected with said sleeve.

100 2. A lock comprising a casing provided with a pair of openings and an integrally formed shackle, a pair of hasps having staples adapted to extend into the casing through said openings, a locking bolt capable when shifted to locking position to extend in opposite directions through said staples whereby the hasps are locked to the casing, means for shifting the said bolt to release the hasps, said hasps slidably and hingedly connected with said shackle.

110 3. A lock comprising a casing provided with a pair of openings and a fixed shackle, a pair of sleeves slidably mounted on the shackle, a hasp member fixed to each of said sleeves and provided with a staple adapted to extend into said openings, a locking bolt capable when shifted to the locking position to extend through said staples, means for shifting said bolt to release said hasps, said means including a plurality of superposed tumblers formed

with recesses engaged by a pin carried by said bolt.

4. A lock comprising a casing provided with a slot, and an integrally formed shackle, a hasp member provided with a staple which latter is adapted to extend into the casing through said slot, a locking bolt capable when shifted to locking position of extending through said staple whereby the hasp member is locked in the casing, means for shifting the said bolt to release the hasp, a sleeve slidably mounted on said shackle, said hasp member fixedly connected with said sleeve, said staple being resilient to permit of its engagement with said bolt while the latter is in the locking position.

5. A lock comprising a casing provided with a pair of openings and an integrally formed shackle, a pair of hasps having staples adapted to extend into the casing through said openings, a locking bolt capable when shifted to locking position to extend in opposite directions through said staples whereby the hasps are locked to the casing, means for shifting the said bolt to release the hasps, said hasps slidably and hingedly connected with said shackle, said staples being resilient to permit of their engagement with said bolt while the latter is in the locking position.

6. A lock comprising a casing provided with a pair of openings and a fixed shackle, a pair of sleeves slidably mounted on the shackle, a hasp member fixed to each of said sleeves and provided with a staple adapted to extend into said openings, a locking bolt capable when shifted to the locking position of extending through said staples, means for shifting said bolt to release said hasps, said means including a plurality of superposed tumblers formed with recesses engaged by a pin carried by said bolt, said staples being resilient to permit of their

engagement with said bolt while the latter is in the locking position.

7. A lock comprising in combination a casing provided with a pair of openings, a flat bar formed integral with said casing and having projecting ends, one of said ends having an angularly disposed arm, a shackle fixed to said arm and extending parallel with said bar, a pair of sleeves slidably and rotatably mounted on said shackle, a hasp member fixed to each of said sleeves and provided with a staple adapted to extend into said casing openings, a locking bolt carrying a laterally disposed pin and adapted to engage said staples when in the locking position, means for shifting said bolt to release said hasps, said staples being resilient to permit of their engagement with said bolt when the latter is in the locking position, a hinged cover plate disposed intermediate of said hasps, a latching element slidably carried by said bar for securing said cover plate in the closed position, a resilient member fixed to said cover plate for throwing the latter to the open position when said latch is released, said bolt shifting means including a plurality of pivoted superposed flat metal tumblers formed with curved recesses aligned relatively to each other, each of said tumblers having an operating lip varying in width with respect to the width of the other of said tumblers, said pin engaging in said recesses of the tumblers for shifting the bolt to the unlocking position when said tumblers are shifted and a resilient member for returning the said bolt to the locking position, substantially as described and for the purpose set forth.

In testimony whereof we affix our signatures.

ANGELO C. MESSINA.
JOSEPH MESSINA.
